LATERAL MOTION DRIVING BOX

Filed June 25, 1923

2 Sheets-Sheet 2

Fig. 5.

UNITED STATES PATENT OFFICE.

SAMUEL S. RIEGEL, OF SCRANTON, PENNSYLVANIA.

LATERAL-MOTION DRIVING BOX.

Application filed June 25, 1923. Serial No. 647,445.

To all whom it may concern:

Be it known that I, SAMUEL S. RIEGEL, a citizen of the United States, residing at Scranton, in the county of Lackawanna and 5 State of Pennsylvania, have invented certain new and useful Improvements in Lateral-Motion Driving Boxes, of which the following is a specification.

My invention relates to lateral motion devices or equipments for the driving or axle boxes of locomotives and other railway vehicles, whether associated with pivoted trucks or with other forms of carriage. While the invention has the same general 10 objects and purposes as the construction shown in United States Patent No. 1,181,194 issued to myself and William E. Woodard, jointly, on May, 2, 1916 (which exemplifies the lateral motion appliances heretofore in 15 general use), and is intended to meet the same general conditions, it also presents important distinctions and advantages of its own, as will hereinafter appear.

By my present invention, I aim to simplify and improve such "lateral motions"; to cheapen their construction; and to enable them to be easily applied to locomotives already built, without the necessity for extensive or costly changes in such locomotives. 25 How these and other advantages can be realized in a novel manner through my invention will appear from my description hereinafter of the best embodiment of the invention known to me.

30 In the drawings, Fig. 1 is a fragmentary side view, partly in section (as indicated by the line 1—1 in Fig. 3), of a railway vehicle axle and its axle boxes, illustrating the application of my present invention thereto.

Fig. 2 is a fragmentary view of the parts at one axle box illustrating the action of the device in service, many of the parts being in 35 section, and the scale being larger than in Fig. 1.

Fig. 3 is a view toward one of the wheels from the inside, with certain parts in section as indicated by the line 3—3 in Fig. 1, and still others partly broken away.

40 Figs. 4 and 5 are fragmentary diagrammatic views similar to Figs. 1 and 3, but on a much smaller scale, illustrating the application of my lateral motion in connection with spring rigging different from that 45 shown in Figs. 1 to 3.

50 Referring to Figs. 1, 2 and 3, it will be

seen that in the present instance my invention is shown applied to a locomotive in connection with the driving wheels of its "main carriage" (so to term it), rather than with wheels of "accessory carriages" or trucks. The locomotive side frames illustrated are of the standard bar type, with top rails A, bottom rails B, and vertical pedestal jaws C for the vertical movement 55 or play of the driving boxes D. The pedestals C may be provided with the usual shoe and wedge means e and f, or their equivalents, for properly guiding and sustaining the driving or axle boxes D, which 60 rest on the axle G of the driving wheels H. Except as hereinafter described, the parts D, G and H may be of standard or any other suitable type and construction. As shown, the outer and inner flanges i and j of the 65 driving boxes D are spaced apart to afford clearance for such lateral movement of the boxes in the jaws C as is required by the locomotive design and the intended conditions of service, and the outer wear faces 70 of the boxes afford lateral thrust bearing at k for the hubs of the drivers. A due proportion of the load of the vehicle weight, etc., is transmitted to the axle boxes D through the usual spring rigging structure 75 L, and other parts now soon to be described.

80 In practice, of course, the pedestal jaws C may be closed at the bottom with the usual pedestal frame binder or tie, and the usual lubricating and other accessory parts 85 may be provided: these, however, are all omitted from the drawings, to avoid confusion.

85 In the present instance, the load is transmitted from the spring rigging structure L 95 to the corresponding driving box D at different points lengthwise of the axle G, through a saddle 14 with depending leg portions 15, 16 to either side of the top rail A. The clearance between the saddle 14 and the 100 top rail A permits the saddle to ride up and down (relative to the frame) with the movement of the box D due to inequalities of the track, and the flexibility and looseness at joints of the spring rigging permit the saddle 105 to rock slightly. As shown, the outer saddle leg 15 is the longer, and rests or bears directly on the box D, in the usual outer fore and aft seat or socket 17. In the present instance, this outer saddle leg 15 is pivoted to the saddle proper at 18. The shorter inner leg 16 rests and bears in a rounded fore an-

aft seat or socket 19 (of appropriate length) in a member or device 20 that is movable up and down relatively to the locomotive frame, but is restrained as against lateral movement. In the present instance, the member 20 is mounted to slide in a guide way formed by flanged vertical guides 21 that are bolted fast against the inner side of the frame bar A, and plates 22 are interposed between the edges of the member 20 and the frame bar A to obviate frictional bearing over the back of the member 20. From the member or device 20, load is transmitted to the box D by means of a member 23 interposed between said member 20 and a part 24 mounted on the box. As here shown (see Figs. 2 and 3), the part 24 has a fore and aft recess in its lower side to accommodate or take over the inner top flange 25 of the box D, and engages or interlocks at 26 (with a reasonably close fit) in the usual inner fore and aft saddle seat 17 just beyond said flange. The overhanging and depending portion of the part 24 may be bolted fast to the box D, as shown.

In the present instance, the load-transmitting member 23 has the character of a double-point rocker, with a long fore and aft pivot back or apex 27 and double fore and aft pivot feet 28, 29. The apex pivot 27 engages and bears in a corresponding rounded fore and aft seat in the lower side of the member 20, and the feet 28, 29 in similar seats in the aforesaid part 24. As here shown, the seats for the outer foot pivots 28 are directly over the inner end or side of the box D, while those for the inner foot pivots 29 overhang beyond the box.

In the present instance, the construction is all just alike at opposite sides of the carriage: in other words, the foregoing description applies to both boxes D and their associated parts.

Fig. 1, especially, shows the normal positions of the parts when the device is properly adjusted and the locomotive is on straight track. The hubs of the wheels H, H abut against the wear faces k, k of the boxes D, D; both feet 28, 29 of each member 23 rest solidly in their bearings in the part 24, and the saddles 14, 14 are level; and there are clearances between the outer and inner axle box flanges i, j at both sides of the carriage, on the one hand, and the corresponding shoes and wedges e, f, on the other hand.

If, now, the vehicle takes a curve with the left-hand wheel H at the outside, the resulting lateral thrust on and from this wheel will shift or displace the left-hand box D inward, to the right, carrying with it the lower end of the saddle leg 15 and the part 24 that seats the rocker feet 28, 29, and thus rocking the member 23 about its upper turning center at 27 in the member 20. Owing to the initial downward and outward incli-

nation or obliquity of the line of centers 27, 28, this counter-clockwise rocking of the member 23 about its pivotal center at 27 will lift the member 20 bodily against the resistance of the vehicle load, tipping the saddle 14 proper about the center 17 or 18, or both. At the same time, the saddle leg 16 will pivot or tilt slightly at 19. As shown, the seat of the saddle 14 is rounded or cambered transversely at 30, so as to "roll" under the spring rigging L, which remains upright. Owing to the shortness of the inner leg 16, the slight tilting of the saddle 14 about the pivotal center at 19 will not cause any appreciable lateral stress or strain in the spring rigging L.

As soon as the vehicle passes from the curve to tangent track and the lateral thrust on the box D is thus relieved, the load acting through the saddle leg 16, the device 20, and the still oblique member 23 will forcibly return the box D to its original position.

When the vehicle takes a reverse curve, a similar action will occur at the other side.

Preferably, provision is made for interconnecting the "lateral motions" at the two sides of the vehicle, so as to bring both into action in resistance to lateral displacement of either axle box D, D. As here shown, this is done by directly interconnecting the boxes D, D themselves, by means of a cross tie 34 integral with the parts 24. With such an interconnection, inward movement of either box D will result in outward movement of the other, and in rocking of the member 23 at the other box on its inner foot 29. With the symmetrical and similar design and arrangement of the rocker members 23, 23 here illustrated, the action will be similar and cumulative at both sides of the carriage for inward deflection of the box D at either side: i. e., the load of the vehicle weight will be brought to bear at both sides in yielding resistance to inward displacement of a box D at either side, so as to return and recenter the parts when the displacing thrust is relieved.

In order to prevent dislocation of parts when the locomotive is lifted with a crane and the usual load on them thus removed, a "lost-motion" connection may be provided between the tie 34 and each saddle 14. As shown, this comprises an adjustable double-nutted ring bolt 35 hooked over a lug or hook 36 projecting from the saddle leg 16 and extending through a hole 37 in or adjacent the end portion 24.

From the foregoing description, it will be seen that the parts involved in the lateral motion are few and simple, and can be readily manufactured and carried in stock as standard equipment. In order to apply such an equipment to an existing locomotive, all that need be done is to remove its saddles; drill and tap its frame members A and its

boxes D in a few places; bolt on the parts 24 and the guides 21, and place the parts 23 between them; and, finally, put the saddle 14 in place and, if desired, the parts 35, 5 etc. Thus the only parts of the locomotive running gear that require replacement or material modification are the saddles.

Figs. 4 and 5 illustrate the general applicability of the invention, regardless of 10 the exact type or form of spring rigging employed. The figures show a spring rigging L' embodying the usual type of equalizers l' whose ends are connected to the springs s, and whose middle portions rest 15 on the shoulders afforded by the notched corners of the saddle 14'. As usual, each of the equalizers l' comprises a pair of interconnected spaced bars—their spacing corresponding to the width of the saddle 20 14' from back to back of its shoulder notches. It will be observed that the saddle 14' shown in Fig. 4 is also applicable to the spring rigging L of Figs. 1 to 3, with the spring resting directly on the cambered 25 seat 30.

What I claim is:

1. The combination with side frames and laterally shiftable axle boxes, of a device for receiving the load of the vehicle weight 30 movable up and down at each frame, but restrained as against lateral movement; oblique load-transmitting members interposed between said devices and boxes, to bring the load of the vehicle weight to bear 35 in yielding resistance to lateral movement of the boxes; and means of cross connection for causing said load-transmitting members at the two boxes to act concurrently.
- 40 2. The combination with side frame and laterally shiftable axle boxes, of a tie interconnecting said axle boxes and affording double bearings at each, a double point rocker for each box engaged in said tie bearings, a device mounted to slide up and down on each of said side frames resting on the corresponding rocker, a spring saddle over each of said side frames with one leg resting on the corresponding axle box and the other 45 on the corresponding device, and means of connection between tie and saddles for preventing dislocation of the parts when relieved of their load.

- 55 3. Lateral motion equipment for a railway vehicle comprising a tie for interconnecting corresponding axle boxes; a device for receiving the load of the vehicle weight mountable for up and down movement beside each side frame of the vehicle, with provision for restraining it as against lateral movement; and load-transmitting members for acting obliquely between the afore-said devices and the corresponding boxes 60 swingable oppositely to bring the load of the vehicle weight to bear at both boxes in

yielding resistance to lateral movement thereof either way.

4. Lateral motion equipment for a railway vehicle comprising a tie adapted to interconnect corresponding axle boxes and afford double bearings at each, double point rockers adapted to work in said tie bearings, a device mountable to slide up and down on each side frame of the vehicle and adapted to rest on the corresponding rocker, and 70 a saddle for transmitting the load of the vehicle weight to each axle box at one side of the corresponding side frame and to the corresponding device at the other side.

5. Lateral motion equipment for a railway vehicle comprising a tie with end portions adapted to rest on top of corresponding axle boxes in interlocking engagement therewith, and affording double rocker bearings on their own upper sides; double 80 point rockers adapted to work in said tie bearings; a device mountable to slide up and down on each side frame of the vehicle and adapted to rest on the corresponding rocker; and a saddle for transmitting the 85 load of the vehicle weight to each axle box adapted to pivot on the corresponding device and at the other side of the corresponding side frame, with provisions for obviating stresses on the spring rigging from 90 movement of said saddles.

6. A railway vehicle lateral motion comprising a device loaded with the vehicle weight movable up and down in a guide way on the vehicle frame, and restrained as 100 against lateral movement; and means for transmitting the load of the vehicle weight from said device to the axle box, and for bringing such load to bear in yielding resistance to lateral movement of the box. 105

7. A railway vehicle lateral motion comprising a device movable up and down relatively to the vehicle frame, but restrained as against lateral movement; a saddle with one leg resting on said device, and the other on the axle box; and a load-transmitting member for acting obliquely between said device and said box so as to bring the load of the vehicle weight to bear in yielding resistance to lateral movement of the box. 110

8. A railway vehicle lateral motion comprising a device movable up and down relatively to the vehicle frame, but restrained as against lateral movement; a saddle with one leg resting on said device, and the other on the axle box; and a double-pointed rocker interposed between said first-mentioned device and said box, for bringing the load of the vehicle weight to bear in yielding resistance to lateral movement of the box 115 120 either way.

9. A railway vehicle lateral motion comprising a device guided to move up and down beside the vehicle frame, and restrained as against lateral movement; a sad- 130

4
dle resting on said device at one side of the vehicle frame, and on the axle box at the other side; and means for transmitting the load of the vehicle weight from said device to said box, and for bringing such load to bear in yielding resistance to lateral movement of the box.

10. A railway vehicle lateral motion comprising a device guided to move up and down beside the vehicle frame, and restrained as against lateral movement; a saddle with rocking bearing on said device at one side of the vehicle frame, and with a pivoted leg at the other side of the frame bearing on the axle box; and means for transmitting the load of the vehicle weight from said device to said box, and for bringing such load to bear in yielding resistance to lateral movement of the box.

11. Lateral motion equipment for a railway vehicle comprising a part mountable on an ordinary axle box; a device for receiving the load of the vehicle weight mountable for up and down movement beside the vehicle frame, with provision for restraining it as against lateral movement; and a member for transmitting the load of the vehicle weight from said device to said first-mentioned part, adapted to act obliquely to bring such load to bear in yielding resistance to lateral movement of the axle box.

12. Lateral motion equipment for a railway vehicle comprising a part adapted to take over a top flange of an axle box and engage in the adjacent saddle seat; a member with up and down guide means therefore mountable at the side of the vehicle frame; a saddle adapted to rest on said member at one side of the vehicle frame, and at

its other side to engage in the other saddle seat of the axle box; and means for transmitting the load of the vehicle weight from said member to said first-mentioned part, and for bringing such load to bear in yielding resistance to lateral movement of the 45 axle box.

13. Lateral motion equipment for a railway vehicle comprising a device for receiving the load of the vehicle weight mountable for up and down movement beside the vehicle frame, with restraint as against lateral movement; a double pointed rocker for sustaining said device; and a part adapted to take over a top flange of the corresponding axle box, and afford double bearing for 50 said rocker over and overhanging said axle box.

14. Lateral motion equipment for a railway vehicle comprising a part mountable on an ordinary axle box; a device for receiving the load of the vehicle weight mountable for up and down movement beside the vehicle frame, with provision for restraining it as against lateral movement; a saddle with 60 rocking bearing on said device at one side of the vehicle frame, and with a pivoted leg at the other side of the frame for transmitting the load of the vehicle weight to the axle box; and a member for transmitting the load of the vehicle weight from said device to said first-mentioned part, adapted to 70 act obliquely to bring such load to bear in yielding resistance to lateral movement of the axle box.

In testimony whereof, I have hereunto signed my name.

SAMUEL S. RIEGEL.
